US00D750666S

(12) **United States Design Patent**
Moon et al.

(10) **Patent No.:** US D750,666 S
(45) **Date of Patent:** ** Mar. 1, 2016

(54) **DISPLAY SCREEN OR PORTION THEREOF WITH ICON**

(71) Applicant: **Samsung Electronics Co., Ltd.,**
Suwon-si (KR)

(72) Inventors: **Ji-Hyun Moon**, Seoul (KR); **Yong-Man Park**, Yongin-si (KR)

(73) Assignee: **Samsung Electronics Co., Ltd.,**
Suwon-si (KR)

(**) Term: **14 Years**

(21) Appl. No.: **29/472,753**

(22) Filed: **Nov. 15, 2013**

(30) **Foreign Application Priority Data**

Sep. 10, 2013 (KR) 30-2013-0046612

(51) **LOC (10) Cl.** **14-04**

(52) **U.S. Cl.** **D14/492**
USPC .....

(58) **Field of Classification Search**

USPC D14/485-495

CPC G06F 3/048; G06F 3/04817; G06F 3/0482

See application file for complete search history.

(57) **CLAIM**

The ornamental design for a display screen or portion thereof with icon, as shown and described.

DESCRIPTION

FIG. 1 is a front view of a display screen or portion thereof with icon, showing our new design; and,

FIG. 2 is a front view of a display screen or portion thereof with icon showing an alternative embodiment of our new design.

The dot-dash broken lines illustrating portions of the display screen or portion thereof with icon are for illustrative purpose only and form no part of the claimed design.

The color of the display screen or portion thereof with icon forms no part of the claimed design.

1 Claim, 2 Drawing Sheets
